UNITED STATES PATENT OFFICE.

ERNEST J. BRASSEUR, OF CHICAGO, ILLINOIS, ASSIGNOR TO A. B. DICK COMPANY, OF CHICAGO, ILLINOIS, A CORPORATION OF ILLINOIS.

ROTARY STENCIL-DUPLICATING MACHINE.

Application filed October 3, 1925. Serial No. 60,158.

This invention relates to rotary stencil duplicating machines.

One of the principal objects of this invention is directed to an improvement in the manner of attaching an ink pad to the machine, and is to provide a construction so constituted that a pad may be replaced on the machine readily and easily without the operator touching any ink-carrying surface, and consequently without dirtying the hands. Another object of this invention is to provide means for so holding a pad in place on the machine that ink is prevented from going beyond the edge of the pad and dirtying other parts of the machine. A further object is to provide pad retaining means which permit the pad to be reversed on the machine, thus extending the life of the pad. The objects of this invention also include the provision of pad retaining means which permit adjustment of the pad on the cylinder.

Another principal object of this invention is to provide improved means for holding a stencil sheet on the pad and cylinder, and to provide clamping means which function to prevent ink from going beyond the edge of the stencil and dirtying adjacent parts of the machine; to relieve the strain between the stencil stub and the buttons engaging the same; to relieve the stub of the stencil sheet from shock as the rubber roller contacts therewith; also to prevent chafing contact of the rubber roller against the stencil sheet, and at the same time to provide a properly located knife edge which facilitates the tearing off of the stencil backing sheet.

Another object of this invention is to provide improved hook means for engaging the stencil stub, permitting the stencil sheet to be more readily and easily attached to and removed from the machine, and permitting adjustment of the stencil lengthwise and angularly with respect to the diaphragm.

A further object of this invention is to provide pad attaching and stencil engaging means which are adjustable to compensate for errors in location of written matter on the stencil.

A further object of this invention is to provide improved pad and stencil attachment means of the character described which may be applied to rotary duplicating ma-

chines which are otherwise of standard construction.

A further object of this invention includes the provision of improved means for locking the printing cylinder against rotation to make the operation of attaching or detaching a pad or stencil easier.

Another object is to provide an improved pad construction which permits reversal of the pad on the machine, whereby the life of the pad may be extended.

A further object of my invention is to provide an improved packing gland which is adjustable so as to be kept in leak-proof condition.

Another object of my invention is to provide a shield or guard for protecting the shaft bearing of the trough or, in other words, as an additional protection in conjunction with the packing from leaking.

Other objects of this invention will be in part obvious and in part pointed out hereinafter.

In accordance with this invention, the ink pad comprises a sheet of suitable fabric having securely and permanently attached at each end a metallic plate provided with perforations. The attachment plates on each end of the sheet are alike, so that the pad can be turned over and reversed on the machine, and in consequence of this feature the life of the pad may be extended.

The means for retaining this pad on the cylinder include fingers which engage the stub at the leading end of the pad and hooks which engage the stub of the pad at the trailing end. At the leading end, the fabric of the pad passes over a bevel edge on the end of the diaphragm. Adjustable hook means are provided for engaging the stub of a conventional stencil sheet, with the fabric of the sheet resting on the ink pad and passing beyond the beveled edge of the diaphragm. The leading edge of the pad and the stencil sheet are engaged and clamped tightly between the stationary bevel edge of the diaphragm and a bevel edge of a movable plate, whereby the strain is relieved between the stencil sheet stub and the said hooks, and the ink is prevented from going beyond the line across which the stencil and pad are clamped. The movable plate protects the stencil from shock and chafing by the rubber roller during operation of the

machine. This bevel edge of the plate also establishes a knife edge across which the backing of the stencil sheet may be torn, thus rendering the removal of this backing easier. At the trailing end of the diaphragm there is a movable plate which may be brought over and clamped downwardly upon the trailing ends of the pad and stencil sheet to prevent ink from going beyond the clamped portion of the sheet and pad.

The said stencil hook means are adjustable toward and from the diaphragm and also angularly with respect thereto to permit similar adjustment of the stencil on the cylinder.

The above and other features of the construction will be described fully and in detail hereinafter.

In order that a clearer understanding of this invention may be had, attention is hereby directed to the accompanying drawings, forming a part of this application and illustrating certain possible embodiments of the invention.

Referring to the drawings: Fig. 1 is a view, partly in section and partly in elevation, of a portion of a rotary stencil-duplicating machine in which the invention has been embodied, this view being taken substantially on the line 1—1 of Fig. 2; Fig. 2 is a top view of the same; Fig. 3 is a sectional view radially through the cylinder, and is taken on the line 3—3 of Fig. 2, a pad and stencil being shown engaged on the cylinder; Fig. 4 is a repetition of a portion of Fig. 3, but shows the clamping means in retracted or releasing position; Fig. 5 is a sectional view of an end fragment of the pad and its attachment plate, and is taken on the line 5—5 of Fig. 12; Fig. 6 is a sectional view of a portion of the cylinder, and is taken on the line 6—6 of Fig. 2; Fig. 7 is a sectional view taken on the line 7—7 of Fig. 6; Fig. 8 is a sectional view of a fragment of the machine showing the means for engaging the trailing end of the pad and showing the movable clamping plate in retracted position, as on 8—8 of Fig. 2; Fig. 9 is a sectional view of a detail, and is taken on the line 9—9 of Fig. 6; Fig. 10 is a side view of the cylinder showing the means for locking the cylinder against rotation and the means for locking the ink tank against tipping, both means being shown as applied to a machine which is otherwise of standard construction; Fig. 11 is a sectional view of a detail of the cylinder locking means, and is taken on the line 11—11 of Fig. 10; Fig. 12 is an elevation of the ink pad with its end attachment plates, the center of the pad being broken away; Fig. 13 is an enlarged detail view showing the sliding mounting of one of the fingers which rests beneath the leading edge of a sheet of paper; Fig. 14 is a sectional view of a portion of a cylinder, in-

cluding a packing gland embodying my invention and an inkshield therefor, also embodying my invention, the view being taken on the line 14—14 of Fig. 15; and Fig. 15 is a sectional view of the same, and is taken on the line 15—15 of Fig. 14. Similar reference characters refer to similar parts throughout the several views of the drawings.

The cylinder and the inking means are in the main similar to the construction shown and described in patent to Ernest J. Brasleur for duplicating machines, No. 1,527,783, February 24, 1925. This construction includes a cylinder comprising side plates or walls 1 and 2, joined together and held in position by a perforated diaphragm 3. The wall plates are provided with the usual cams 4 which control other parts of the machine. A closed compartment 5 is provided within the cylinder and behind the diaphragm 3, and an ink trough 6 is suspended within this compartment by being rigidly secured to the shaft 7, about which the cylinder rotates. The cylinder is supported on suitable side brackets 8 and 9. The ink pad 10 is placed over the diaphragm 3, and the stencil sheet 11 is placed over the pad in the usual position. When it is desired to apply ink to the pad, the trough 6 is tilted, by rocking a handle 12 secured to a shaft 12' which is connected with an end of the rod 7 by collars 7' and 9', which have pin and slot engagement, as at 19. The cylinder may be rotated by the usual handle 13, and during this rotation the ink which has been spilled from the trough upon the diaphragm will spread thereover and permeate into and through the ink pad. When the cylinder is stopped with the diaphragm uppermost, ink drops therefrom back into the trough 6. This is in accordance with the disclosure in the patent before mentioned.

As shown best in Fig. 12, the ink pad 10 comprises a sheet of suitable material, to each end of which is fixed a metal attachment strip 14. Each attachment strip is permanently attached to the sheet in the manner best shown in Fig. 5, that is, by first doubling the edge of the plate upon itself with the edge of the sheet in between, and then folding this double portion over again in such a way that a rounded edge 15 of one of the folds of the plate extends beyond the extreme edge 16 of the plate. With this arrangement the sheet 10 does not contact any sharp edges of the plate but bears against the rounded edge 15, and thus is securely held without danger of being cut or ripped away. Each plate 14 is provided with a pair of perforations 17, to the rear of which are tapered offset portions 18, which serve to guide the plates into engagement with engaging fingers or hooks mounted on the cylinder. Since plates 14 are alike, the sheet may be turned over and reversed on

the cylinder, and by periodically turning and reversing the sheet its life can be extended.

Across the cylinder at the leading end of 5 the diaphragm is a plate 20, which carries two prongs or fingers 21 positioned to engage within the pair of perforations 17 on one of the pad plates 14. At the trailing end of the diaphragm a rod 22 extends 10 across the cylinder, and is positioned to have the end of the fabric of the pad brought over and partially around it, with the edge of the plate 14 engaging beneath the rod. A pair of members 23 are pivotally mounted 15 on the drum, each member 23 having preferably a series of hooks 24, which may be engaged selectively with one of the perforations 17 of the trailing plate 14 of the pad to hold this end of the pad securely on the 20 cylinder. The provision of the series of hooks 24 permits the taking up of slack should the pad stretch. To take up such slack, it is only necessary to engage a lower finger 24 of one or both devices 23 in the 25 perforation in the plate 14. By this arrangement, an inking pad can be readily and easily removed from the machine without it being necessary for the operator to dirty his hands with ink from the pad. To 30 detach a pad, the operator grasps the plate 14 at the trailing edge of the pad and disengages this plate from the devices 23. The operator then peels the pad from the cylinder, and then, by rotating the cylinder so 35 that the fingers 21 are directed downwardly, the operator need merely lower the other end of the pad and it will automatically fall away from the fingers 21, and become entirely free of the machine. In putting 40 a pad in place, the same operations are carried out but in reverse order, that is, the operator grasps the plate at the trailing end of the pad and moves the pad to place the leading plate into engagement with the 45 fingers 21. Then he preferably rotates the cylinder and simultaneously lowers the sheet to lay it over the diaphragm, and then engages the trailing plate 14 with the devices 23. As will be clear, the operator 50 may do all this without grasping any part of the pad except the plate at the trailing edge of the pad. As no ink is allowed to get onto this plate, the operator's fingers 55 will be clean of ink.

The stencil stub 25 has the usual button-hole perforations, and is engageable over hooks 26, carried on a plate 27, which is adjustably mounted between the side walls of the cylinder. Each end of plate 27 is fixed 60 to an arm 30, as by rivets 31, which penetrate elongated slots 32 in a stationary cross-bar 33 attached at its ends to the cylinder walls 1 and 2. A screw 34 is swiveled in the rear of each arm 30 and is in threaded 65 engagement with a bracket 35 fixed to a

cross-bar 33 at each end. Thus, by turning the screw 34 which is adjacent cylinder wall 1, the adjacent end of plate 27 may be adjusted toward and from the adjacent end of the diaphragm. Similarly, by adjusting the screw 34 which is near the cylinder wall 2, the corresponding end of plate 27 may be adjusted toward and from the adjacent edge of the diaphragm. By properly adjusting both screws 34, a stencil sheet 70 engaged over the buttons may be adjusted on the diaphragm into the most suitable position thereon. In order that the operator may readily ascertain whether the stencil stub and sheet are in proper alignment with 75 the cylinder, each arm 30 has a pointed finger 36 bent over bracket 35, and each bracket 35 has a cooperating indicating mark 37, whereby the operator, by noting the relative positions of these fingers with respect 80 to the marks 37, may readily and easily determine whether or not the plate 27 and the hooks thereon are parallel with the end of the diaphragm, and may effect this adjustment by adjusting the arms 30 into such 85 positions that each finger 36 is in the same relative position to its cooperating indicating mark 37 as is the finger of the other arm with respect to its cooperating mark. Each arm 30 also has a finger 38 bent under 90 bracket 35 to coact with finger 36 to provide a guide for each arm on each bracket.

Mounted on each wall 1 and 2 is a stud pin 40 on which is pivoted at one end an arm 41 which at its end has a slot 42 through 100 which extends a bolt 43 secured to the cylinder wall and having a washer and nut 44, whereby the arm 41 may be locked in adjusted position on the cylinder. Adjacent pin 40, arm 41 has an eccentric pin 45 which pivotally supports an arm 46. The top portions 47 of arms 46 extend toward the diaphragm. Extending between and rigidly secured to these top portions 47 is a plate 48 which has the same curvature as the periphery of the diaphragm. Plate 48 has a beveled edge 49. This edge may be taken against or away from a complementary bevel edge 50 provided on the adjacent edge of the diaphragm 3, by causing arms 46 to 110 pivot on the stud 45. A rod 51 extends between and is secured to the opposite arms 46. At the center of this rod is engaged one end 52 of a toggle couple 53; the other end 54 of the toggle couple being pivoted on 115 a pin 55 carried on a pair of brackets 56 which are mounted on the top of the cylinder ink chamber. The toggle is provided with a finger piece 57 to render it easy to extend or to collapse the toggle.

To the under side of plate 48 is secured an angular piece of sheet metal having flanges 60 secured to plate 48 and having a wall 61 which at its ends has flanges 62 welded to the portions 47 of the opposite arms 46. 120

Wall 61 has cut outs 63 for the hooks 26, the arrangement being such that when plate 48 is clamped against the diaphragm, the portions of wall 61 adjacent the hooks will move the stencil stub 25 home on the hooks 26 before the stencil sheet is clamped between the bevel edges 49 and 50.

The operation of the aforementioned clamping means is as follows: When an ink 10 pad and stencil sheet are to be attached to the machine, the clamping means should be in retracted position, as shown in Fig. 4. The stencil pad is now engaged by causing the fingers 21 to engage in the perforations 15 17 of the pad attachment plate 14. The pad is then carefully laid on the diaphragm and its opposite end is secured by the attachment devices 23 in the manner heretofore described. The stencil sheet with its backing 20 attached is then secured to the machine by engaging its stub over the hooks 26. The stencil sheet is then carefully laid over the pad. If adjustment of the stencil sheet is necessary, the hooks are adjusted by manipulating the screws 34 in the manner referred 25 to above. Then the operator takes hold of finger 57 and presses the same inwardly toward the cylinder. This causes toggle couple 53 to become extended and at the same time causes the plate 48 to move edge-wise toward the adjacent edge of the diaphragm and finally to press tightly against the diaphragm edge to clamp the ink pad 30 and stencil tightly between these edges. 35 However, before this tight clamping has been effected, the member 61 will have engaged the stencil stub and will have pushed it home on the hooks 26. The function of levers 41 is to raise or lower the surface of 40 the plate 48 so that it will be always a little higher than the stencil irrespective of wear on the pivots or manufacturing errors.

Having clamped the stencil with its backing attached and the pad at this end of the 45 diaphragm, the backing of the stencil sheet may now be torn off readily and easily along the knife edge presented by the end of plate 48 which is clamped thereagainst. As before stated, the top surface of plate 48 is 50 raised just a trifle above the surface of the stencil sheet, so that as the machine operates this plate will receive the shock from the rubber roller, and also will protect the stencil sheet against chafing contact from 55 this roller.

On the rear edge of plate 48 are two downwardly extending lugs 65 which carry a bolt 66. From each end of bolt 66 extends a bar 67 which at its other end is pivotally 60 secured to one of the arms 46, and here is supplied with a mutilated collar 68 against which engages a spring 69 whereby the bar is held yieldably in either of two positions of rotation on the arm 46 and bolt 66. Each 65 bar 67 carries a slide 70 for adjustment

thereon, and secured to each slide is a grooved conventional finger 71 which is disposable between the stencil and a sheet to be printed to hold the sheet for engagement by the conventional sheet ejecting pin (not shown). These fingers with the bars 67 are pivotable to allow these fingers to be placed against or away from the stencil sheet. 70

At the trailing end of the diaphragm is a movable plate 75 having at each side edge a pair of lugs 76 and 77. Mounted against lugs 76 and 77 is a dog 78 and opposite lug 76 on the opposite side of dog 78 is secured an arm 79 of a U-shaped bar, the top of which 80 extends across the cylinder, and the arms 79 being pivoted to the cylinder walls as at 81. Parts 76, 78 and 79 are connected by a pin 82.

Extending between the lugs 77 is a rod 83, which at its center is engaged by an end 84 of a toggle couple 85. At its other end 86, this toggle is mounted on a pin 87 supported on two brackets 88 which are attached to the top of the ink chamber. This toggle has a finger 89 for operating the same. A spring 90 is coiled around pin 82 and has its opposite ends engaging cross bar 80 and rod 83. This spring aids in taking the plate 75 against the diaphragm. The forward ends of dogs 78 are recessed 90 to receive rod 22, thereby establishing a fulcrum about which the plate 75 pivots when the toggle approaches fully extended position and causes the end of plate 75 to clamp the pad and stencil tightly and firmly 95 against the diaphragm. 100

A guide member 91 is secured to one wall 2 of the cylinder, and a roller 93 is mounted on the outside of the adjacent dog 78 to ride on the surface 94 of the guide 91. This surface has a depression 95 at its rear end in which the roller 93 is arrested when the plate 75 is in fully retracted position. 105

The operation of the clamping mechanism at this end of the diaphragm is as follows: The ink pad and stencil sheet having been laid on the cylinder and engaged at their leading ends in the manner above described, the plate 75 is taken from its retracted position (see Fig. 8) into its forward or clamping position (see Fig. 3), by the operator taking hold of the toggle finger 89 and pressing this inwardly toward the cylinder to cause toggle 85 to become extended. During this movement of the toggle couple, the forward edge of plate 75 is taken over the adjacent edge of the diaphragm and the ink pad and stencil sheet thereon. This movement accompanies the movement of swinging pivot 79 and until further movement of this swinging pivot is prevented by the dogs 78 coming in contact with the rod 22. Then further extension of the toggle couple will cause the plate 75 to pivot on the pivots 82 in such a way that the rear edge 110 115 120 125 130

of the plate will rise and the forward edge will be tightly pressed against the diaphragm and will clamp the ink pad and the stencil sheet tightly between the plate and the diaphragm. To retract plate 75 to permit removal of a stencil sheet or an ink pad, it is only necessary for the operator to grasp toggle finger 89, and, by pulling this finger outwardly of the cylinder, cause the toggle couple to collapse, with the consequent withdrawal of the plate from the diaphragm. When the toggle couple is in fully collapsed condition, the rollers 93 forming a part of this clamping mechanism will automatically become located in the recesses 95 of the guide members 91, and the clamping mechanism will be yieldingly held in retracted position.

The clamping mechanism at each end of the diaphragm may be assembled into composite units before being mounted in the machine. For instance, parts 41, 46, 48 and 51 may comprise one unit. Parts 27 and 33 and parts carried thereby may comprise another unit.

If the cylinder walls 1 and 2 have the usual flanges 100, then in order to permit the attachment of these assemblies to the machine, the flanges 100 may be cut away as at 101. This will permit of the insertion of the assembly units into their proper positions between the cylinder walls. Then these cut away portions may be filled with removable inserts 102 and 103, which may be removably secured to the cylinder walls as by screws 104 and 105. One insert 102 may, if desired, carry the conventional crank button 106 used to connect the cylinder with automatic driving means in the usual manner. Inserts 103 are preferably integral with guide members 91.

Counter-balance weights 107 may be secured to the cylinder walls to properly balance the cylinder.

There is also illustrated herein an improved stuffing box and gland. This comprises a housing 110 about rod 7, the housing being threaded at its outer end, as at 111, and here extends through the side wall 112 of the closed ink chamber 5. Within the inner end of housing 110 there is packing 113 about rod 7, and abutting the end of this packing is a sleeve 114. A cap nut 115 threaded on the end of housing 110 bears against the outer end of sleeve 114, whereby, by screwing this cap nut, the sleeve 114 may be forced inwardly against the packing 113, thus creating even pressure on the packing and insuring a leak proof, rotational mounting of the cylinder and housing 110 on rod 7. The stuffing box cap 115 may be locked in adjusted position by means of a resilient bar 123 which is secured to counterweight 107 and has a straight end disposed against a straight side of the cap. The bar being

resilient may be bent away from the cap when adjustment is to be made.

At the opposite side of the cylinder the wall 1 has a bushing 116, and this wall is held in place on bracket 8 by means of a stub shaft 117 which may be locked in place by means of a set screw 118 which is threaded in bracket 8 and carries a locking lug 119 into and out an annular recess 120 in shaft 117 to allow or to prevent disengagement of shaft 117 from cylinder wall 1 and the removal of the cylinder from its supports. Preferably a click spring 121 rests against a knurled knob 122 of screw 118.

If desired, means may be provided for locking the cylinder against rotation and means may also be provided for locking the handle 12 against rotation to tip the ink trough 6. To this end an arm 125 is secured to frame 9, and has an end adjacent the tripper handle 12. This handle has an offset shoulder 126 which is arranged to come against arm 125 to prevent rotation of handle 12 to the left. A spring pressed latch 127 is pivotally mounted on arm 125 and has a prong 128 which engages in a recess 129 in handle 12 to prevent turning of handle 12 to the right (Fig. 10) to spill the ink. When it is desired to spill the ink latch 127 is retracted and the ink trough 95 tipped by manipulating handle 12.

The main object of locking the trough is to prevent accidental or inadvertent spilling of ink therefrom. With this arrangement, should a person or an object come in contact with handle 12, ink will not be spilled from the trough. However, the operator may readily and easily tip the trough to deliver ink to the diaphragm when he desires to do so.

The lock for the cylinder comprises a plunger 130 on arm 125 and a housing 131 secured to this arm. A coil spring 132 urges the outer end of the plunger, which is preferably tipped with leather as at 133, against the cylinder wall. This plunger has a pin 134 extending through a bayonet slot 135 in one side of housing 131 permitting the plunger to be locked in retracted position. This lock for the cylinder serves several useful purposes. It holds the cylinder against rotation when it is desired to remove or to attach a stencil sheet or an ink pad without requiring the operator to place a hand on the cylinder to prevent this rotation. The engagement being frictional, it permits the operator to rotate the cylinder into different positions without releasing the lock. When the machine is not in use, it is usually preferable to position the cylinder so that the diaphragm is uppermost, in which position ink drains into the ink trough within the sealed compartment. The lock maintains the cylinder in this adjusted position and prevents accidental displacement thereof.

In Figs. 14 and 15 there is shown a device for shielding the packing housing 110 from ink which drips downwardly. This device comprises a sheet metal box-like member 140, which is U-shaped and attached in inverted position about the housing 110 and the adjacent portion rod 7. At one side shield 140 may have secured thereto a flange member 141, which establishes with the adjacent side wall of the member 140 a trough or groove 142, which directs ink into the ink trough 6. Shield 140 may be secured in place by means of bolts 143, which penetrate a wall of the shield 140 and engage in slots 144 of a bracket or frame piece 145, which is seated in trough 6 and has flanges 146 secured thereto. The stop collar 147 and its set screw 148, which is mounted on shaft 7 to prevent inward movement of packing 20 gland 110, is also preferably within cover 140. It will be apparent that ink dripping downwardly will flow around the top of the shield and around the trough 142 into the ink trough 6, and that this ink will be prevented from contacting the packing housing 110. In this manner the ink, or the oily constituents thereof, are prevented from finding their way into the packing 113.

As shown, the side walls 112 of the sealed ink compartment 5 have inwardly directed edge flanges 150 on which the side edges of the diaphragm 3 rest. By providing registering perforations in these flanges 150 and the diaphragm, and filling the perforations with solder, the diaphragm may be conveniently secured to these flanges very securely. These members are thus keyed together by the solder, which will be exposed on the outside of the diaphragm along its side edges, as at 40 151. The keys on opposite edges of the diaphragm may be so aligned that the line drawn between two opposite aligned keys across the diaphragm or a stencil thereon will establish a line which is exactly parallel 45 with the axis of the cylinder. Thus, to ascertain whether or not the lines of printing on a stencil are parallel with the cylinder axis and will fall straight across the paper sheet to be printed, it is only necessary to 50 place a straight edge across the stencil and in alignment with two corresponding keys. If alignment is not proper, it may be remedied by changing the angular adjustment of the stencil by manipulating screws 55 34, as before described. To aid in recognizing corresponding keys, the flanges 100 of the cylinder walls 1 and 2 may be provided with indicating scales, as at 153.

As many changes could be made in the 60 above construction and as many apparently widely different embodiments of this invention could be made without departing from the scope thereof, it is intended that all matter contained in the above description or 65 shown in the accompanying drawings shall

be interpreted as illustrative and not in a limiting sense.

What I claim is:—

1. In a rotary stencil duplicating machine, in combination, a cylinder having a diaphragm, an ink pad, attachment plates secured to each end of the pad, and means adjustable on the cylinder at each end of the diaphragm engageable with said attachment plates for securing the pad in place over the diaphragm. 75

2. In a rotary stencil duplicating machine, in combination, a cylinder having a diaphragm, an ink pad, attachment plates secured to each end of the pad, and means adjustable on the cylinder at each end of the diaphragm engageable with said attachment plates for securing the pad in place over the diaphragm, said attachment plates being alike, and the said means at each end of the diaphragm being engageable with either plate, and the pad being reversible on the diaphragm. 80

3. In a rotary stencil duplicating machine, in combination, a cylinder having a diaphragm, an ink pad, an attachment plate secured to one end of said pad, and means on the cylinder engageable with said plate for securing the pad to the cylinder, said plate having attachment perforations, and said means comprising pivoted fingers at one end of the diaphragm engageable in said perforations. 90

4. In a rotary stencil duplicating machine, in combination, a cylinder having a diaphragm, an ink pad, an attachment plate secured to one end of said pad, and means on the cylinder engageable with said plate for securing the pad to the cylinder, said plate having attachment perforations, and said means including a pivoted member at one end of the diaphragm having a hook engageable in one of said perforations. 100

5. In a rotary stencil duplicating machine, in combination, a cylinder having a diaphragm, an ink pad, an attachment plate secured to one end of said pad, and means on the cylinder engageable with said plate for securing the pad to the cylinder, said plate having attachment perforations, and said means comprising pivoted devices at one end of the diaphragm, each having a series of hooks engageable selectively in one of said perforations. 110

6. In a rotary stencil duplicating machine, in combination, a cylinder having a diaphragm, an ink pad, an attachment plate secured to one end of said pad, and means on the cylinder engageable with said plate for securing the pad to the cylinder, said plate having attachment perforations, a rod at one end of the diaphragm constituting a bearing for the fabric at one end of the pad, and said attachment means comprising pivoted devices at said end of the diaphragm, 120

125

130

each having a series of hooks engageable selectively in one of said perforations, the rear edge of said plate being engageable below said rod, and said hooks constituting means for varying the amount of turn of fabric about said rod to compensate for variations in the length of the pad.

7. In a rotary stencil duplicating machine, in combination, a cylinder having a diaphragm, an ink pad, an attachment plate secured to one end of said pad, means on the cylinder engageable with said plate for securing the pad to the cylinder, and means mounted on said cylinder at one end of the diaphragm and movable against the pad at one end of the diaphragm for preventing ink from passing from the pad onto the adjacent attachment plate.

8. In a rotary stencil duplicating machine, in combination, a cylinder having a diaphragm, an ink pad, attachment plates secured to each end of the pad, means on the cylinder at each end of the diaphragm engageable with said attachment plates for securing the pad in place over the diaphragm, and means mounted on said cylinder at each end of the diaphragm and movable against the pad at each end of the diaphragm for preventing ink from passing from the pad onto either of its said attachment plates.

9. In a rotary stencil duplicating machine, in combination, a cylinder having a diaphragm, an ink pad, attachment plates secured to each end of the pad, and means on the cylinder at each end of the diaphragm engageable with said attachment plates for securing the pad in place over the diaphragm, one of said plates being accessible to permit the pad to be engaged on or to be removed from the cylinder without requiring the operator to touch any part of the pad but said plate.

10. An ink pad of the character described, comprising, in combination, a sheet of fabric, and an attachment plate secured to the fabric at one end of the sheet, the edge of the sheet being interfolded with an edge of said plate, and said sheet where it leaves said plate bearing against the rounded base of a fold in the plate, whereby the adjacent edges of the pad and plate are securely held together and the sheet is protected from being cut by the extreme edge of the plate.

11. An ink pad of the character described, comprising, in combination, a sheet of fabric, and an attachment plate secured to the fabric at one end of the sheet, said plate having attachment perforations and having inclined offset guide channels immediately to the rear of said perforations.

12. In a rotary stencil duplicating machine, in combination, a cylinder having a diaphragm, a stencil sheet having a button-holed stub, buttons engageable with said

stub, and means for retaining said buttons on said cylinder for adjustment toward and from one end of said diaphragm, whereby the stencil sheet may be adjusted on said diaphragm.

13. In a rotary stencil duplicating machine, in combination, a cylinder having a diaphragm, a stencil sheet having a button-holed stub, buttons engageable with said stub, and means for retaining said buttons on said cylinder for adjustment toward and from one end of said diaphragm, whereby the stencil sheet may be adjusted on said diaphragm, said means including a cross-plate on which the buttons are carried, an arm secured on each end of said plate, a bracket fixedly attached to the cylinder, adjacent each arm, and a screw swiveled in each arm and threaded into the adjacent bracket, whereby the arms and buttons may be adjusted in accordance with the adjustment of the screws on the brackets.

14. In a rotary stencil duplicating machine, in combination, a cylinder having a diaphragm, a stencil sheet having a button-holed stub, buttons engageable with said stub, and means for retaining said buttons on said cylinder for adjustment toward and from one end of said diaphragm, whereby the stencil sheet may be adjusted on said diaphragm, said means including a cross-plate on which the buttons are carried, an arm secured on each end of said plate, a bracket fixedly attached to the cylinder, adjacent each arm, and a screw swiveled in each arm and threaded into the adjacent bracket, whereby the arms and buttons may be adjusted in accordance with the adjustment of the screws on the brackets, each arm having a pointer and each bracket having a cooperating indicating mark, whereby the relative adjustment of each arm and bracket is readily ascertainable.

15. In a rotary stencil duplicating machine, in combination, a cylinder having a diaphragm, a stencil sheet having a button-holed stub, hooks engageable with said stub, and means for retaining said buttons on said cylinder for adjustment toward and from one end of said diaphragm, whereby the stencil sheet may be adjusted on said diaphragm, said means including a cross-plate on which the buttons are carried, an arm secured on each end of said plate, a bracket fixedly attached to the cylinder, adjacent each arm, a screw swiveled in each arm and threaded into the adjacent bracket, whereby the arms and hooks may be adjusted in accordance with the adjustment of the screws on the brackets, and a cross-bar secured to the cylinder and extending beneath said cross-plate, whereby said cross-plate is guided in its movements of adjustment.

16. In a rotary stencil duplicating machine, in combination, a cylinder having a

diaphragm, a stencil sheet having a stub, means on the cylinder for engaging the stencil stub beyond an edge of the diaphragm to hold the stencil on the cylinder, and means for clamping the stencil sheet against the adjacent edge of the diaphragm to relieve the strain between the stub and the stub-engaging means.

17. In a rotary stencil duplicating machine, in combination, a cylinder having a diaphragm, a stencil sheet having a stub, means on the cylinder for engaging the stencil stub beyond an edge of the diaphragm to hold the stencil on the cylinder, and means for clamping the stencil sheet against the adjacent edge of the diaphragm to relieve the strain between the stub and the stub engaging means, said clamping means presenting a knife edge across the stencil sheet along 10 which the backing of the stencil sheet may be torn, whereby the removal of this backing is facilitated.

18. In a rotary stencil duplicating machine, in combination, a cylinder having a diaphragm, a stencil sheet having a stub, means on the cylinder for engaging the stencil stub beyond an edge of the diaphragm to hold the stencil on the cylinder, and means for clamping the stencil sheet against the adjacent edge of the diaphragm to relieve the strain between the stub and the stub engaging means, said clamping means also constituting means for preventing ink from passing from the stencil sheet beyond the point where the sheet is clamped against the diaphragm.

19. In a rotary stencil duplicating machine, in combination, a cylinder having a diaphragm, a stencil sheet having a stub, means on the cylinder for engaging the stencil stub beyond an edge of the diaphragm to hold the stencil on the cylinder, and means for clamping the stencil sheet against the adjacent edge of the diaphragm to relieve the strain between the stub and the stub engaging means, said clamping means including a plate disposable edgewise tightly against an edge of the diaphragm, with the stencil sheet intermediate the said edges of the plate and diaphragm.

20. In a rotary stencil duplicating machine, in combination, a cylinder having a diaphragm, a stencil sheet having a stub, means on the cylinder for engaging the stencil stub beyond an edge of the diaphragm to hold the stencil on the cylinder, and means for clamping the stencil sheet against the adjacent edge of the diaphragm to relieve the strain between the stub and the stub engaging means, said clamping means including a plate disposable edgewise tightly against an edge of the diaphragm, with the stencil sheet intermediate the said edges of the plate and diaphragm, said edges of the

plate and diaphragm having complementary 65 taper.

21. In a rotary stencil duplicating machine, in combination, a cylinder having a diaphragm, a stencil sheet having a stub, means on the cylinder for engaging the stencil stub beyond an edge of the diaphragm to hold the stencil on the cylinder, and means for clamping the stencil sheet against the adjacent edge of the diaphragm to relieve the strain between the stub and the 70 stub engaging means, said clamping means including a plate disposable edgewise tightly against an edge of the diaphragm, with the stencil sheet intermediate the said edges of the plate and diaphragm, said top surface 75 of said plate being a slight amount above the stencil sheet.

22. In a rotary stencil duplicating machine, in combination, a cylinder having a diaphragm, a stencil sheet having a stub, means engaging said stub beyond an edge 80 of the diaphragm to hold the stencil on the cylinder, an arm pivotally carried on each side wall of the cylinder, a plate secured to said arms and having its forward edge presented toward said edge of the diaphragm, a rod secured to and extending between said arms, and toggle means secured to said cylinder and to the center of said rod, whereby when said toggle means are extended said 85 plate edge is clamped tightly against the said edge of the diaphragm with the stencil sheet intermediate said plate and diaphragm edges, and when said toggle means is broken said plate is withdrawn from said 90 diaphragm and said stencil stub is free to be disengaged from the stub engaging means.

23. In a rotary stencil duplicating machine, in combination, a cylinder having a diaphragm, a stencil sheet having a stub, means engaging said stub beyond an edge 95 of the diaphragm to hold the stencil on the cylinder, an arm pivotally carried on each side wall of the cylinder, a plate secured to said arms and having its forward edge presented toward said edge of the diaphragm, a rod secured to and extending between said arms, and toggle means secured to said cylinder and to the center of said rod, whereby 100 when said toggle means are extended said plate edge is clamped tightly against the said edge of the diaphragm with the stencil sheet intermediate said plate and diaphragm edges, and when said toggle means is broken said plate is withdrawn from said 105 diaphragm and said stencil stub is free to be disengaged from the stub engaging means, said rod being flexed when said toggle 110 is extended whereby the plate edge is yielded 115ingly held tightly against the diaphragm edge.

24. In a rotary stencil duplicating ma-

chine, in combination, a cylinder having a diaphragm, a stencil sheet having a stub, means engaging said stub beyond an edge of the diaphragm to hold the stencil on the cylinder, 5 an arm pivotally carried on each side wall of the cylinder, a plate secured to said arms and having its forward edge presented toward said edge of the diaphragm, a rod secured to and extending between said 10 arms, and toggle means secured to said cylinder and to the center of said rod, whereby when said toggle means are extended said plate edge is clamped tightly against the said edge of the diaphragm with the stencil sheet intermediate said plate and diaphragm edges, and when said toggle means 15 is broken said plate is withdrawn from said diaphragm and said stencil stub is free to be disengaged from the stub engaging means, a lever pivoted on each cylinder wall, 20 means for locking each lever in adjusted position, a pin on each lever located eccentrically of its pivot point, and said arms being pivotally mounted on said pins, whereby 25 said arms and the plate carried thereby may be adjusted on the cylinder in response to pivotal adjustment of said levers.

25. In a rotary stencil duplicating machine, in combination, a cylinder having a 30 diaphragm, a stencil sheet having a stub, means on the cylinder for engaging the stencil stub beyond an edge of the diaphragm to hold the stencil on the cylinder, and means for clamping the stencil sheet against the adjacent edge of the diaphragm to relieve the strain between the stub and the 35 stub-engaging means, said stencil stub having attachment perforations, buttons secured beyond said diaphragm edge and engageable in said perforations, and means co-acting with said clamping means for forcing said stub home on said buttons.

26. In a rotary stencil duplicating machine, in combination, a cylinder having a 45 diaphragm, a stencil sheet having a stub, means on the cylinder for engaging the stencil stub beyond an edge of the diaphragm to hold the stencil on the cylinder, and means for clamping the stencil sheet against the adjacent edge of the diaphragm to relieve 50 the strain between the stub and the stub-engaging means, said stencil stub having attachment perforations, buttons secured beyond said diaphragm edge and engageable 55 in said perforations, and means co-acting with said clamping means for forcing said stub home on said buttons, said clamping means including a plate movable edgewise against said diaphragm edge to clamp the 60 stencil sheet between the plate and diaphragm, and said coacting means including a member secured beneath said plate for movement therewith and having portions 65 movable downwardly alongside said buttons to force the stencil stub home before the

stencil sheet is clamped by said clamping means.

27. In a rotary stencil duplicating machine, in combination, a cylinder having a diaphragm, a stencil sheet disposable over 70 the diaphragm, and means on the cylinder for clamping the stencil sheet near its bottom edge tightly against the diaphragm.

28. In a rotary stencil duplicating machine, in combination, a cylinder having a 75 diaphragm, a stencil sheet disposable over the diaphragm, and means on the cylinder for clamping the stencil sheet near its bottom edge tightly against the diaphragm, 80 said means including a plate movable on the cylinder into and out of overlapping position with respect to the stencil sheet when in place on the diaphragm.

29. In a rotary stencil duplicating machine, in combination, a cylinder having a 85 diaphragm, a stencil sheet disposable on the diaphragm, a plate movable on the cylinder into and out of overlapping position with respect to the lower portion of the stencil sheet when in place on the diaphragm, 90 and means for clamping said plate tightly downwardly against the stencil sheet and diaphragm.

30. In a rotary stencil duplicating machine, in combination, a cylinder having a 95 diaphragm, a stencil sheet disposable on the diaphragm, a plate movable on the cylinder into and out of overlapping position with respect to the lower portion of the stencil sheet when in place on the diaphragm, 100 and means for clamping said plate tightly downwardly against the stencil sheet and diaphragm, said plate being mounted on a swinging pivot attached to the cylinder and said clamping means including a toggle for rotating said plate on said swinging pivot.

31. In a rotary stencil duplicating machine, in combination, a cylinder having a diaphragm, a stencil sheet disposable on said diaphragm, a cross-member pivoted on said cylinder to swing toward and from one end of the diaphragm, a plate pivoted intermediate its front and rear edges on said cross-member and movable therewith into and out of position overlapping the stencil when in place on the diaphragm, a rod secured to the two side edges of said plate near its rear edge, and a toggle couple secured at one end to said rod and at its other end to said cylinder, whereby when said toggle is extended said plate is disposed to overlap said stencil and is rotated on its swinging pivot to firmly clamp downwardly on said stencil and diaphragm, and when said toggle is collapsed said clamping pressure is released and said plate and its swinging pivot is withdrawn from said stencil and diaphragm.

32. In a rotary stencil duplicating machine, in combination, a cylinder having a 130

diaphragm, a stencil sheet disposable on said diaphragm, a cross-member pivoted on said cylinder to swing toward and from one end of the diaphragm, a plate pivoted intermediate its front and rear edges on said cross-member and movable therewith into and out of position overlapping the stencil when in place on the diaphragm, a rod secured to the two side edges of said plate near its rear edge, and a toggle couple secured at one end to said rod and at its other end to said cylinder, whereby when said toggle is extended said plate is disposed to overlap said stencil and is rotated on its swinging pivot to firmly clamp downwardly on said stencil and diaphragm, and when said toggle is collapsed said clamping pressure is released and said plate and its swinging pivot is withdrawn from said stencil and diaphragm, and spring means engaging said rod and cross-member for urging said pivot and plate toward the diaphragm.

33. In a rotary stencil duplicating machine, in combination, a cylinder having a diaphragm, a stencil sheet disposable on said diaphragm, a cross-member pivoted on said cylinder to swing toward and from one end of the diaphragm, a plate pivoted intermediate its front and rear edges on said cross-member and movable therewith into and out of position overlapping the stencil when in place on the diaphragm, a rod secured to the two side edges of said plate near its rear edge, and a toggle couple secured at one end to said rod and at its other end to said cylinder, whereby when said toggle is extended said plate is disposed to overlap said stencil and is rotated on its swinging pivot to firmly clamp downwardly on said stencil and diaphragm, and when said toggle is collapsed said clamping pressure is released and said plate and its swinging pivot is withdrawn from said stencil and diaphragm, a roller movable with said cross-member and plate, and a guide member for said roller secured to a wall of said cylinder.

34. In a rotary stencil duplicating machine, in combination, a cylinder having a diaphragm, a stencil sheet disposable on said diaphragm, a cross-member pivoted on said cylinder to swing toward and from one end of the diaphragm, a plate pivoted intermediate its front and rear edges on said cross-member and movable therewith into and out of position overlapping the stencil when in place on the diaphragm, a rod secured to the two side edges of said plate near its rear edge, and a toggle couple secured at one end to said rod and at its other end to said cylinder, whereby when said toggle is extended said plate is disposed to overlap said stencil and is rotated on its swinging pivot to firmly clamp downwardly on said stencil and diaphragm, and when

said toggle is collapsed said clamping pressure is released and said plate and its swinging pivot is withdrawn from said stencil and diaphragm, and spring means engaging said rod and cross-member for urging said pivot and plate toward the diaphragm, a roller movable with said cross-member and plate, a guide member for said roller secured to a wall of said cylinder, and a depression rearwardly on said guide member in the path of said roller and constituting means for arresting said roller to hold said cross-member and plate in retracted position against the action of said spring.

35. In a rotary stencil duplicating machine, a cylinder having circular walls flanged inwardly at their edges, a diaphragm on said cylinder, a separate stencil clamping assembly extending between the cylinder walls and beneath said wall flanges, portions of said flanges being cut away to permit the mounting of the stencil clamping assembly on the cylinder.

36. In a rotary stencil duplicating machine, a cylinder having circular walls flanged inwardly at their edges, a diaphragm on said cylinder, a separate stencil clamping assembly extending between the cylinder walls and beneath said wall flanges, portions of said flanges being cut away to permit the mounting of the stencil clamping assembly on the cylinder, and separate insert members secured to the cylinder walls at said cut away portions.

37. In a rotary stencil duplicating machine, a cylinder having circular walls flanged inwardly at their edges, a diaphragm on said cylinder, a separate stencil clamping assembly extending between the cylinder walls and beneath said wall flanges, portions of said flanges being cut away to permit the mounting of the stencil clamping assembly on the cylinder, and separate insert members secured to the cylinder walls at said cut away portions, one of said insert members including an adjustable drive pin device.

38. In a rotary stencil duplicating machine, a cylinder having circular walls flanged inwardly at their edges, a diaphragm on said cylinder, a separate stencil clamping assembly extending between the cylinder walls and beneath said wall flanges, portions of said flanges being cut away to permit the mounting of the stencil clamping assembly on the cylinder, and separate insert members secured to the cylinder walls at said cut away portions, one of said insert members including a tail portion constituting a guide for the roller of clamping mechanism.

This specification signed this 25th day of September, 1925.

ERNEST J. BRASSEUR.
